J. Mc Adams.
Paging Mach.
No. 9038. Patented Mar. 29, 1853.

UNITED STATES PATENT OFFICE.

JOHN MCADAMS, OF BOSTON, MASSACHUSETTS.

IMPROVEMENT IN PAGING BOUND BOOKS.

Specification forming part of Letters Patent No. 9,638, dated March 29, 1853; antedated September 29, 1852.

To all whom it may concern:

Be it known that I, JOHN MCADAMS, of Boston, in the county of Suffolk and State of Massachusetts, have invented a new and useful Method of Numbering the Pages of Books; and I do hereby declare that the following is a full, clear, and exact description of the construction and mode of operation of the machine for performing the same, taken in connection with the accompanying drawings, making part of this specification, in which--

Figure 1 is a front elevation. Fig. 2 is a side elevation. Fig. 3 is a front elevation of that part of the machine which performs the printing, drawn to a larger scale; and Fig. 4 is a vertical transverse section of the same, taken through the middle of the type-chains.

The subject-matter of my invention relates, principally, to a new method of printing the numbers upon the pages of blank books after they are bound; and it consists in applying the types so as to print simultaneously upon opposite sides of the alternate leaves, and thus complete the work as it progresses, and in a new manner of constructing and combining the several parts of the machine, so as to effect the printing of the odd and even numbers of the alternate leaves of the bound book by one movement of the treadle worked by the foot of the operator.

The same letters of reference in the description indicate like parts in all the figures.

A is the frame of the machine, upon which the several parts are mounted, as shown.

B is the table upon which the book is laid when paged, as shown in Fig. 1.

C C' are the upper and lower jaws of the printing apparatus. The upper jaw, C', is made movable, being hinged to the lower one at c. The lower jaw, C, is fixed, and is secured to the bracket B', which projects back from one of the frames of the machine, as shown. These jaws are made of the form shown, so as to receive the shafts D D', around each of which one of the type-chains E E', respectively, pass. That part of the shaft which is embraced by the type-chain is made square, and of a diameter equal to the width of the several links of the chain, so that it embraces the shaft firmly and is held steady when the impression is given, and is carried forward when the shaft is turned. The shafts D D' hang near the outer extremity

of the jaws, so that when the upper jaw is vibrated the shaft D' moves through considerable distance. Near one end of each shaft is a square part, a, upon which the spring a' bears, by which the shaft is held in the proper position to present the types truly to give the impression. b b are ratchets upon the shafts D D', of four teeth each, corresponding to the four sides of the shafts. They are worked by pawls b' and levers d, which turn upon the shafts as fulera, as is shown more distinctly in Fig. 4. The outer ends of the levers d are each attached to one end of the links e, the other end of which is attached to the opposite jaw of the machine, so that when the jaws are opened and closed it produces a quarter-revolution of each of the shafts in a perfectly obvious manner.

The type-chains E E' are made of metallic plates, hinged together in the form of an endless band, as shown, upon which the stereotyped figures are soldered. The upper chain, E', is furnished with the even numbers, 2 4 6, &c., in regular succession, and the lower one, E, with the odd ones, 1 3 5, &c., in the same manner. They are made of sufficient length to receive a series of numbers sufficient to page any ordinary book. The chains are supported when the printing takes place and are carried forward between the impressions by the shafts D D', as already described. They are supported at the other extremity upon the pulleys g, around which they pass.

F is a plate of metal, which is hinged at one end at c, called the "tongue" or "separator," which is placed between the two leaves of the book which are being printed and serves as a platen to each chain of types. f is a bridle which is attached to one side of the tongue, which is made to serve the double purpose of preventing the jaws from opening too wide, and also of bringing the tongue to an intermediate position when the jaws are opened, as shown in Fig. 4, to permit the leaves to be readily inserted above and below it.

G is an endless belt, made of mole-skin or ribbon, called the "smut-belt," which passes around the outer end of the tongue and along each side of it, as shown, and serves as a tympan-sheet to each series of types. It is made to move along a short distance at each impression, being carried by the pulleys g over

which it passes, which also sustain the type-chains and are carried by them as before described. For this reason the pulleys *g* are made with two scores so as to receive both. The smut-belt is further guided for convenience by the pulleys *g*.

H is a forked rod, which is attached at its upper end to the upper jaw, *C*, and leads down to the treadle *I*, by which the machine is worked.

J is a counterpoise upon the treadle to raise it when relieved by the foot.

K is a standard, which is fastened to the floor at a distance from the machine according to the length of the type-chains, upon which are arranged the several pulley-stands, as shown, for supporting the type-chains and smut-belt.

L in Fig. 1 represents a section of a book in the position in which it is placed when it is paged. The two leaves extended horizontally show their position when they are printed. Those that are bent up show their position before they are printed, and those which hang down their position afterward.

The operation of the machine is as follows: Before commencing to page a book both the type-chains are inked with a hand-inking roller, such as is used by printers, and the chains are carried along until the figure 2 of the upper chain and the number next preceding, 1, of the lower chain are brought opposite each other, ready for the impression. The book is then laid upon the table *B* with the covers turned back, as shown in Fig. 1. It is then placed in such a position that when the leaves are extended naturally they will be in proper relation to the types which are to give the impression, so as to print the number in the right place on the page. The operator sitting in front of the machine then leans the right arm upon the book to hold it, and seizes the whole mass of leaves with the right hand by the corner next the printing apparatus, and bends them up out of the way, as shown in Fig. 1. The first leaf to be paged is then detached by the left hand and placed between the tongue and copper chain, the leaf being extended to its natural position, as shown by the horizontal leaves in Fig. 1. The impression is then given by the foot, which prints upon the upper side of the leaf the number 2. The foot is then raised, which opens the jaws, and by the operation of the ratchets and their appendages, before described, each of the shafts *D* is turned one-fourth of a revolution, which brings the next number in each chain to the proper position to be printed. The leaf that was before printed is then passed below the tongue to receive an impression

from the lower chain, and the next leaf is detached from the mass in the right hand and inserted in its place. The impression is again given, which prints the number 1 upon the under side of the first leaf and the number 4 upon the upper side of the second. The operation of discharging the lower leaf, passing the upper one below the tongue, and inserting a fresh leaf above it is repeated at each impression until the book is finished. Thus an accurate registering of the printing with any required margin is produced by simply holding the book fixed and bringing the leaves to be printed to their natural position, the others being bent out of the way above and below them, as shown.

The principles of my invention are susceptible of considerable variety in construction and application. Thus, instead of figures, letters or words may be used, if required, and a chain of types may be used in a machine of this description having the address of persons thereon for the purpose of printing the address of subscribers upon the envelopes of newspapers and for other similar purposes; or but one chain may be used with all the numbers thereon in consecutive order, as 1 2 3, &c., for the purpose of paging letter-copying books when the number is printed only on one side of the leaf; and, so, instead of the endless smut-belt of mole-skin above mentioned a fillet of paper may be used, not made endless, but unrolled from one coil onto another, and I have so used it with advantage; or the fillet may be used with the mole-skin upon the outside of it, which will give a more elastic impression. When the machine is used constantly, the use of the paper fillet is necessary; but when used only occasionally, it is not necessary.

Now, I do not claim the use of type-chains for paging books, as they have already been secured to me by Letters Patent granted August 12, 1851; but

What I do claim as new, and desire to secure by Letters Patent, is—

The employment of the square rotating shaft *D* as a bed for the odd numbers and the shaft *D'* as a bed for the even numbers of the types, in combination with the tongue *F* as a platen to both sets of types, the same being operated by the treadle, ratchets, and pawls, so as to enable the operator to print the odd and even numbers of the alternate pages of a bound book by a single movement of the treadle, as above described.

Boston, December 31, 1851.

JOHN MCADAMS.

In presence of—

WM. C. HIBBARD,
JAS. W. RUTTER.
